UNITED STATES PATENT OFFICE

1,965,979

TABULATING MACHINE

Clair D. Lake, Binghamton, George F. Daly, Johnson City, and Francis E. Hamilton, Endicott, New York, assignors, by mesne assignments, to International Business Machines Corporation, New York, N. Y., a corporation of New York

Application April 19, 1932, Serial No. 606,120

5 Claims. (Cl. 235—92)

This invention concerns accounting machines and more particularly machines of the record controlled tabulator type shown and described in the patent to George F. Daly and Ralph E. Page, No. 1,896,540, filed March 30, 1928 and issued February 7, 1933.

The broad object of the invention is to provide a tabulating machine of improved selectivity of operation and of increased utility together with simplification and improvement of the wiring and switching arrangements and improvement of the mechanical structure with a view to imparting additional operating features as well as improvement in and increased efficiency and utility of the features previously found in such machines.

A more specific object of the invention is the provision of a three speed motor for driving the machine in which the speed and torque characteristics are such that slow speed operation is secured for all alphabetical printing work, intermediate speed is secured for all numerical printing and a much higher speed is obtained during non-print operations. Provision is made for automatically changing the type of operation in accordance with the character of the work being performed. For instance, where the machine is to alphabetically indicate (that is, print alphabetically only during the first card cycle) and numerically list, slow speed operation will obtain during the first card cycle and the intermediate speed will obtain during subsequent card cycles. If the character of the work to be performed calls for alphabetical indicating and tabulating the machine will operate at slow speed for the first card cycle and at high speed thereafter. Incidental to the foregoing, means are provided for securing a high starting torque in the motor when the same starts, this high starting torque being provided automatically and without any attention or manipulation by the operator.

Other objects reside in the general simplification of the machine as a whole, the simplification or elimination of manual control devices heretofore employed, and in changes in the wiring of the machine to the general end that less skill is required of the operator of the machine.

It is a further object of the invention to extend the usefulness of machines of this type by providing an improved printing mechanism which may be called upon when occasion requires to print either numerals or alphabetical characters. An improved form of differential type controlling mechanism is provided and de-

signed to be controlled by a single card column which may select for printing either alphabetical or numerical characters arranged in groups, which characters are far in excess of the number of index points in a card column.

Various other objects and advantages of our invention will be obvious from the following particular description of one form of mechanism embodying the invention or from an inspection of the accompanying drawings; and the invention also constitutes certain new and novel features of construction and combination of parts herein-after set forth and claimed.

In the drawings:

15 Figs. 25, 25a and 25b placed one above the other form a complete wiring diagram of the electric circuits of the machine. In the following description, the terms "counter" and "accumulator" are used interchangeably. The word "counter" as used will have the same meaning as "accumulator" and should be so understood.

Card feed section

20 The machine Fig. 1 comprises a card feeding section generally designated 10, a printing unit 11, accumulating counters 12 and inverting counters 13.

25 Referring to Figs. 1 and 7 the tabulator motor TM by means of belt and pulley connection 14 drives a gear train 15 through a suitable one revolution card feed clutch (not shown) to reciprocate the oscillating link 16 of the card feed mechanism causing it to feed a card to the analyzing brushes for each machine cycle. The pulley through another gear train 17 drives the listing shaft 18 of the machine which in turn as will be later explained, drives the counter operating shafts.

30 The card feed section 10 is provided with the usual supply hopper 19 and receiving hopper 20 and the usual upper analyzing brushes UB and lower analyzing brushes LB shown diagrammatically on the wiring diagram Figs. 25a and 25b, are placed intermediate the hoppers to sense the perforations in the record cards as they pass from one to the other. The cards pass brushes UB and LB successively so that they are analyzed by brushes LB exactly one machine cycle after they are analyzed by the brushes UB.

35 A card of the type analyzed by brushes UB and LB is shown in Fig. 16, the coding arrangement being as illustrated in Fig. 17. It will be noted that in the alphabetical section of the card the letters of the alphabet employ digit punching with an accompanying zone designation in the "X" and "R" index point positions. These two positions are analyzed by the upper brushes UB for controlling certain of the type elements as will be described later. The upper brushes also analyze "Account No." for controlling purposes in the usual manner for effecting group total printing and counter resetting operations.

40 The subtracting operation as carried out by the machine is fully explained in the copending application of George F. Daly, Serial No. 499,279, filed December 1, 1930, in which the use of inverting counters is set forth so that the explanation of the counters in the present case will be confined to the features which are essential to an understanding of the present invention. A subtracting tabulator as in such application is controlled from perforated records in which items to be subtracted, for instance debit and credit items, are entered in the same card columns in their true value. Cards bearing one type of item, for example, debit cards, are provided with a distinguishing perforation adapted to cooperate

50 with the upper analyzing brushes to select one of two accumulators for entry of the items. Items from the other class of cards, for example, credit cards or those having no distinguishing perforation, may be entered into the other accumulator. This provides for a summation of all debit items in one counter and all credit items in another counter.

55 During accumulating and listing operations, the card feed mechanism 10, printing mechanism 11, accumulating counters 12, and inverting counters 13 are driven by tabulating motor TM. Cards, perforated to represent numerical data in the usual manner, and also alphabetically coded characters, are placed in hopper 19 and are fed one at a time through the analyzing devices of the machine. The upper and lower brushes cooperate to automatically control the machine, keeping it in operation if certain classification data on successive cards agree and either stop the machine or effect total taking if the classification data change. As each card passes the lower brushes LB, the latter serve to close control circuits for each card perforation in the numerical data fields of the card which cause 100 operation of the accumulating and printing mechanism to totalize and print the items represented upon the cards.

60 The present machine as previously explained may subtract by adding complements of negative items. Such items are picked from the cards by the upper analyzing brushes which effect a set up in the inverting counters which later enter the corresponding complements into the accumulating counters during the following machine cycle when the cards having caused the setup are passing the lower brushes.

Counter entering mechanism

65 The list shaft 18 (Fig. 4) drives the counter shafts 21 of the accumulators 12 of which there are six, arranged in columns of three in the upper section of the machine. This drive is through gearing 22 to the counter shaft of one set of three counters and through a gear 23 on 120 such shaft to a similar gear on the other shaft (see also Fig. 3).

70 This arrangement is for convenience, to reduce the longitudinal dimension of the tabulator. List shaft 18 through bevel gearing designated 125 24 (Figs. 1 and 7) also drives a shaft 25 which in Fig. 4 drives counter shaft 26 of the inverters through spur gears 27.

75 The several counter elements are operated by magnetically controlled clutches in the usual manner which are energized from the analyzing brushes at differential times in accordance with perforations in the cards to enter and totalize items on the counter elements. The entering mechanism of these machines is well known and fully described in the Patent No. 1,822,594 of C. D. Lake, issued September 8, 1931. It is illustrated in Figs. 3 and 18 and will be briefly described to aid in an understanding of the entering operation of the accumulators and inverters. 130 The counter elements are shown at 30 and may be driven by attached gears which mesh with gears 31 loose on shaft 32. Sliding clutch elements are splined to shaft 32 so that they are driven therewith but may be slid into or out 135 of clutching engagement with gears 31. Each clutch element is provided with a circumferential groove into which projects one end of a pivoted shift lever 33. The shafts 32 are driven during adding cycles from counter shafts 21 and 140 150

26 through gearing 34 at a constant rate. By shifting the lever 33 at different times during the cycle, different degrees of rotation of the counter elements 30 may be effected. The shift lever 33 is controlled by a magnet 35, the armature of which normally engages a latch block on the shift lever to hold the latter in unclutching position. The rear end of the lever engages a flat spring which constantly tends to shift the 10 lever 33 to clutching position.

The magnets may be energized at different times during the adding cycle by timed electrical impulses initiated by the card analyzing brushes of the machine, these impulses occurring 15 according to the location of perforations on the cards. Thus when a card having a perforation representing a certain digit passes the analyzing brushes, the magnet 35 is energized at a time corresponding to the value of the digit and at- 20 tracting its armature, releases the lever 33. The flat spring thereupon shifts lever 33 and the latter forces the constantly running clutch element into engagement with its cooperating element on gear 31. The counter element is thereupon 25 driven from shaft 32 until the end of the adding cycle when the clutch is disengaged by the usual kick-out plate. The movement of a counter element is thus proportional to the value of the digit represented by the perforation on the record card.

The flat spring forms part of a contact assembly consisting of two pairs of contacts one of which is normally closed and the other open. The tripping of lever 33, will effect reversal of 30 the position of these contacts and their functions will be explained hereinafter in connection with the circuit diagram. Both the accumulating counters and the inverting counters are provided with the same entering mechanism.

40 Counter read-out mechanism

Referring to Fig. 18, each clutch gear 31 of both types of counters in addition to driving its 45 counter element, also has driving connection with a gear 38 to which is secured a double brush structure 39.

By virtue of the gear connections shown brush structure 39 will be advanced to occupy different- 50 positions in accordance with the setting of its associated counter element in which positions it will form an electrical connection between a segment 40 and a common conducting strip 41. These segments 40 are numbered 1 to 9 and with 55 a counter element standing at any significant figure its brush 39 will stand at the corresponding segment. In the inverter counters 13 (Fig. 3) an additional segment 40 is provided in the zero position whose function will appear in connection 60 with the explanation of the wiring diagram.

It has already been explained in what manner items are entered into the inverters from the upper brushes. These items are subsequently read from the inverters as complements, during 65 the passage of the card by the lower brushes and entered into the accumulators 12. The reading-out is controlled by an emitter 42 (Fig. 21) which comprises a ring of insulating material carrying a series of conducting segments 43. The emitter 70 42 is mounted on the card feeding section 10 of the machine (Fig. 1) in such manner that a brush structure 44 secured to one of the cycle shafts of the card feed makes one revolution for each card cycle during which brush 44 contacts successively 75 with segments 43 in synchronism with the sensing

of corresponding card index-point positions by the lower brushes. All of the corresponding segments 40 in the read-out section except the units order segments section of the inverter are electrically connected to one another, that is, all the "1" segments are connected to a common wire, all the "2" segments and so on.

Each connected column of segments 40 is connected in complementary arrangement to the emitter segments 43 in such manner that all the "1" segments 40 are connected to the "8" segment 43; all the "2" segments 40 to the "7" segment 43; all the "3" segments 40 to the "6" segment 43; and so on. In the units order the segments 40 are connected to segments 43 in accordance with the "tens" complementary arrangement so that "1" segment 40 is connected to "9" segment 43; "2" segment 40 is connected to "8" segment 43; "3" segment 40 is connected to "7" segment 43; and so on.

Current impulses are emitted from brush 44 in succession to spots 43 and thence to segments 40, then through brush structures 39 to strips 41 and thence to the selected counter magnet 35 of the accumulating counter in which the complement 100 is to be entered. To illustrate, assume brush 39 to be positioned in its "7" position opposite "7" segment 40. As brush 44 rotates, a circuit will be completed when it reaches its "2" segment 43 at "2" in the card cycle of the machine. Since it 105 has been pointed out that the "2" segment is connected to all "7" segments 40, the impulse to the "2" segment 43 will be transmitted to "7" segment "40" and through brush 39 to the proper magnet 35 thereby causing a "2" to be entered in such 110 position. The circuits involved will be traced in detail in connection with the description of the wiring diagram.

In a somewhat similar manner impulses are emitted to the read-out devices of the accumu- 115 lators 12 during total-taking operations to transfer the items or totals standing in the accumulators to the printing mechanism. Referring to Fig. 14 the machine during total and reset operations is driven by the reset motor RM which 120 through a suitable worm and worm wheel 45 drives the total shaft 46.

The usual one revolution clutch 47 is provided to clutch shaft 46 to worm wheel 45 under control 125 of reset clutch magnet 48. Energization of clutch magnet 48 attracts its armature to which clutch arm 49 is attached and rocks the latter, releasing the clutch to permit the completion of the driving connection. Rotation of shaft 46 causes operation of the type bars in a manner to be ex- 130 plained in connection with the description of the printing section and during the passage of the type elements past printing position impulses will be emitted from the read-out devices of the accumulators to cause printing of the items con- 135 tained therein. The emission of impulses is synchronized with the travel of the type bars and the emitters 49 (Figs. 1, 4 and 19) of which there is one for each accumulator 12 are provided with segments 50 and a brush 51 which makes contact 140 with segments 50 in the order 9, 8, 7 . . . as the corresponding type elements 9, 8, 7 . . . pass printing position. The brushes 51 of these emitters are driven from shaft 46 through gearing 52 and impulses are transmitted from brush 51 through 145 segments 50 to segments 40 of the accumulators. The detailed tracing of the circuits involved will be taken up in connection with the wiring dia- 75 gram. This total taking occurs during the first half of the revolution of shaft 46.

Resetting mechanism

During the second half of each revolution of total shaft 46 the counter elements of the accumulating counters 12 may be reset or restored to zero. The total shaft 46 (Figs. 4 and 14) is provided with a mutilated gear 53 having gear teeth about half its periphery and carrying a semicircular metallic plate about the other half of its periphery.

10 This gear through a geneva movement drives a gear 54 (see also Fig. 1) fixed to the reset shaft 55 for the forward set of counters 12. The reset shaft 56 of the rearward set of counters is driven from the forward reset shaft 55 through a train of gears 57 (see Fig. 2). Resetting of individual counter banks may be effected by clutching the shaft on which the counter elements are mounted to the respective reset shafts. Each accumulating counter may be clutched to the reset shaft 55 or 56 electro-magnetically by magnets 58 (Fig. 1) causing engagement of the reset clutches 59 as explained in Patent No. 1,775,132, issued to C. D. Lake et al. and dated September 9, 1930.

20 The resetting of the inverter counters 13 is effected from counter drive shaft 26 (Fig. 4). The inverter counters, of which there are four, as has already been explained are separated into pairs of two and the time of operation of each pair is arranged so that they perform their functions of reading-in, reading-out and resetting in alternate machine cycles. It has already been explained that while one pair of counters 13 is receiving entries from the upper brushes the other pair is controlling the accumulating counters, after which it is zeroized. The zeroizing operation takes place during the reading-out cycle in the following manner and is made possible by the fact that in this type of counter mechanism resetting of the counter elements and brushes 39 (see Fig. 18) is effected by advancing the elements and brushes from their set position to zero, that is, to reset a counter element set at 8, it is advanced two steps to zero.

25 Since as has been pointed out above, the reading-out emitter 49 is sending impulses to the segments 40 and brushes 39 in the order 9, 8, 7 . . . and that these impulses are directed inversely to segments 0, 1, 2, 3 . . . so that immediately after an impulse has been transmitted through, say the "2" segment 40, the brush 39 may be picked up for resetting. In this manner all of the brushes 39 are picked up in succession after the reading-out impulse time for their respective positions and shortly after the last position impulse is emitted all brushes 39 will be left standing at zero.

30 In Figs. 1, 2 and 4, reset shafts 60 and 61 control the resetting of their associated pairs of inverters 13. Each shaft has a gear 62 secured at one extremity thereof which is driven from counter drive shaft 26 through a mutilated gear 63. The toothed portions of these two gears 63 are positioned at an angle of 180 degrees with respect to one another so that while shaft 60 is being driven shaft 61 is idle and vice-versa.

Read-out circuit selecting contacts

35 Contact devices in the form of gang-operated contacts are provided in association with each of the accumulating counters 12 whose function is to connect the reading-out devices for control of the printing circuits whenever desired and to prevent undesirable back-circuits during entering operations.

40 Referring now to Figs. 2, 3 and 18, each coun-

ter 12 has mounted therein, adjacent to its read-out commutator a plurality of contacts 64 the majority of which are normally open, being held in such position by a ball 65 of insulating material which has a latching arm 66 normally held in the position shown in Fig. 18 by a latching armature 67 of trip magnet 68.

45 Upon energization of magnet 68, arm 66 is released and ball 65 rocks in a counterclockwise direction to permit shifting of contacts 64 to their alternate position. Ball 65 is positively restored to latching position during the resetting operation of the counter by means of a cam 69 mounted on reset shaft 55 or 56. Rotation of cam 69 will rock a lever 70 about its pivot and through adjustable screw and nut connection with an arm 71 secured to the pivot rod of ball 65 will restore the ball to latched position.

Auto control contacts

50 The usual automatic control contacts are shown at 72 in Fig. 3 together with their controlling magnets 73. The restoring cams for these contacts are carried by a shaft 74 which is driven from list shaft 18 (Fig. 4) through gearing 75.

Numerical printing mechanism

55 In Figs. 7, 13 and 14 the listing shaft 18 has a notched disc 76 fixed to it, and the listing box cam 77 is free on the listing shaft and carries a pawl 78 provided with a nose adapted through spring action to engage in the notch in disc 76 when the pawl is released to cause the box cam 77 to rotate with the listing shaft. This box cam 77 in the usual manner causes the numerical type bars to reciprocate for printing purposes during listing operations. An extending tail piece of pawl 78 coacts with a notch in lever 79 which holds the nose portion of the pawl out of contact with the disc 76 thereby preventing rotation of the list cam 77 with the list shaft 18. The lever 79 is operated by a scissor mechanism comprising arms 80 and 81. The lever 79 is fixed relatively to the arm 80 and a suitable spring urges it to totalizing position. A list non-list lever 82 in the position shown in Fig. 7 permits these scissor elements to come together allowing the lever 79 to remain in latching position.

60 If the list non-list lever 82 is pulled downwardly as in Fig. 13 an attached sliding link 83 provided with cam edges at its free end prays the scissor elements apart and causes the lever 79 to rock counterclockwise releasing the pawl 78, whereupon the listing box cam 77 is clutched to the listing shaft and rotates with it.

65 At the end of a listing operation the pawl 78 remains engaged with the disc 76 so that even though the lever 82 be thereafter shifted for a tabulating operation the listing cam will make one revolution during which group data may be printed from the first card of the following group. Means are also provided forleasing the arm 79 temporarily during each total taking cycle to permit the pawl 78 to move to clutching engagement thus also providing for the first printing cycle of the following card group. At the end of this cycle, of course, assuming the machine is set for straight tabulating the arm 79 having moved back to normal position, the tail of pawl 78 will engage the notch in the lever and cause it to unclutch. A pair of contacts LC-2 is controlled by the arm 81 so that it will open when the listing cam is in normal position but will be closed if the list non-list lever 82 is moved to upper or list-

ing position. The arm 81 is provided with an extension carrying a roller at its end which coacts with a notch in the list box cam 77. When this cam is in normal position the roller engages the 5 notch and holds the cam against displacement. During the rotation of the box cam in the first tabulating cycle the arm 81 is lifted by the cam 77 and the contacts LC-2 are closed during this first tabulating cycle. The purpose of these cam contacts is to insure low speed whenever the tabulator is performing printing operations as will be explained in connection with the circuit diagram.

During a total and reset operation magnet 48 15 is energized as explained and through levers 84 (Fig. 14) connected to its armature will rock shaft 85 carrying lever 79. This rocks lever 79 to release pawl 78 permitting it to engage the tooth of ratchet 76 and drive the box cam 77.

20 Printing must be effected during listing cycles and during total taking cycles. Operation of the type bars is effected from the list box cam 77 during listing cycles and from the total shaft 46 during totaling cycles. Referring to Figs. 5 and 14 the numerical type bars shown at 86 are operated from a rock shaft 87 which may be rocked either from the listing cam or the total taking shaft. The shaft 87 (see Figs. 6 and 14) has a two arm member 88 fixed to it. An arm 89 freely 25 rotatable on shaft 87 carries a roller which projects into the slot of listing box cam 77; another arm 90, also freely rotatable on shaft 87 carries a roller cooperating with total print cam 91. Member 88 has a set screw in one arm normally 30 engaging the upper side of a sidewise lug carried by an arm 90. A lug in the other arm of member 88 is normally engaged on its upper side by a set screw in arm 89. When the listing cam 77 rotates, its groove rocks the arm 89 clockwise, 35 while when the total cam 91 rotates, it rocks the arm 90 clockwise. Either operation, owing to the cooperation of the lugs and set-screws results in clockwise rocking of the two armed member 88 and consequently the shaft 87 to which it is pinned. Fixed to this shaft are arms 92 pivoted 40 at their free ends through suitable links 93 to frame 94 guided for vertical movement by rails 95 (Figs. 5, 8 and 14) which cooperate with rollers 96 carried at the extremities of frame 94.

45 Type bars 86 are mounted for sliding motion in the frame and an extension 97 on each type bar takes under a portion of the frame against which it is pressed by a spring pressed lever 98 one of which is provided for each type bar 86 and is 50 pivoted on a bracket on the frame. As long as there is no interference with the movement of the type bars they move upwardly with the frame 94 but they may be stopped at any point without interference with the motion of the frame; the arm 98 in this case being pressed downwardly against the action of its spring.

55 Each type bar 86 is provided with a rack portion having one tooth for each type carried by the bar. The type bars are stopped in proper position to correspond to the perforations in the controlling records or to the data on the accumulators by printing magnets 99. A pull wire 100 attached to the magnet armature may operate a latch 101 causing it to release a corresponding stop pawl 102 spring pressed to engage the rack teeth on bar 86. Energization of any of the magnets 99, then, causes the pawl 102 to stop further upward movement of the corresponding type bar. At the end of the normal upward movement 60 of all the type bars arms 103 pivoted to arms 92 release a spring pressed bail 104 causing it to operate all the printing hammers 105 and print on the platen 106 from the selected type. On the ensuing downward movement of the frame 85 the latter engages the extensions 97 on the type bars and restores them to normal position.

Alphabetical printing mechanism

Referring to Fig. 6 list cam 77 carries a gear 107 which through an idler and further gear connection drives a box cam 108 so that cam 108 makes one revolution for every revolution of cam 77. A bell crank shaped cam follower arm 109 (see also Fig. 10) has its follower roller extending into the groove of cam 108. The arm 109 is loosely mounted on a rod 110 and has resilient stud and spring connection to an arm 111 fixed to shaft 110 which also carries arms 112 (see also Fig. 8) having link connection at their free ends to frame 113. Frame 113 is guided for vertical movement by suitable rollers 114 and guide rails 115 in a manner similar to frame 94 and during listing operations both frames move together in the same direction to control the positioning of the alphabetical type bars 86a. 100 Each type bar 86a has associated therewith a differential pinion 116 and a rack 117. Rack 117 is carried by frame 94 and moved upwardly therewith through the spring pressed lever 98a stopping of the upward movement of rack 117 105 is effected in the same manner as the stopping of the type bars 86 through the tripping of pawl 102a under control of magnet 99a.

105 Pinion 116 is carried by the upper end of a link 118 and is normally held in the position 110 shown in Fig. 6 by a spring pressed latch 119 pivoted to the fixed frame of the machine. Provision is made for coupling link 118 to frame 113 as the latter is elevated. With the parts in the position of Fig. 6, energization of zone-selecting magnet 120 will rock spring-pressed camming arm 121 in a counterclockwise direction to the position of Fig. 9, thereby moving spring-pressed plunger 122 to the left into engagement with latch 119 to rock the latter out 120 of engagement with link 118.

115 Further upward movement of frame 113 while magnet 120 remains energized will result in the engagement of the hooked end of plunger 122 with the lower extremity of link 118 as shown, 125 so that continued advance of frame 113 will carry link 118 and pinion 116 therewith. Energization of magnet 120 after plunger 122 has passed the end of link 118 will result in moving plunger 123 to the left under control of cam 130 arm 121. In the same manner as plunger 122, the plunger 123 will rock latch 119 to unlatching position and couple link 118 to frame 113. The manner and time of energization of magnet 120 is controlled by a zone selecting mechanism to be described later. If magnet 120 does not receive an impulse during the elevation of frame 113, link 118 remains in latched position holding pinion 116 stationary so that as frame 135 94 rises and carries with it rack 117, type bar 86a will be lowered to successively present the type elements arranged above the printing line to the platen 106. Interruption of the upward movement of rack 117 will halt the downward movement of bar 86a and printing will later be 140 effected from one of the type elements in zone 1 of the type bar. The type elements included in zone 1 corresponds to the characters shown in the zone 1 field of the code in Fig. 17. These 145 are the usual digit perforations and control 150

printing from zone 1 of the type bar 86a in the manner just traced.

The characters in zone 2 all include an "x" perforation which through the zone selecting mechanism will cause operation of plunger 123 to cause selection of a type element in the control section of the type at the same time that rack 117 differentially selects a particular one of the type in said zone in accordance with the 10 digit perforation accompanying the "X" hole.

In like manner the "R" hole accompanying the zone 3 characters effects movement of plunger 122 to elevate pinion 116 so that type selection may be made in the lowest zone of the type.

15 It is to be noted that during listing operations both frames 94 and 113 are operated to effect selection of any of the type elements on bar 86a while during total printing operations, only frame 94 is operated so that only zone 1 20 of the type bar is moved through printing position. This permits the printing of totals at greater speed since only digits are selected at such times.

As shown in Figs. 6 and 12 pawls 102a are 25 positively restored by a bail 124 fixed to a rocking frame 125 which serves to restore all of the latches at a predetermined part in the cycle regardless of whether it is a listing or totaling cycle. The frame 125 is rocked by a lever 126 30 loose on shaft 87 and having one arm coacting with a cam 127 loose on list shaft 18 which is driven from list cam 77 through gear 107a (Fig. 14) shaft 107b and gears 107c and another arm coacting with a cam 128 on total cam shaft 35 129 which is geared to the total shaft 46 (see also Fig. 14). Operation of either the listing cam or total shaft then effects rocking of the frame 125 to restore stop pawls 102a.

Restoration of camming levers 121 is effected 40 by a heel 130 integral with frame 113 (Figs. 6 and 9) which, as the frame is elevated engages the levers 121 to rock them positively in a clockwise direction.

Zone selecting mechanism

45 As the record cards traverse the upper brushes UB, the index-point positions "X" and "R" are analyzed to determine from which zone of the type bar 86a the particular characters are to be printed. This selecting is controlled by the mechanism shown in Fig. 15 which shows a unit plate carrying selecting devices for four columns of the record card. This arrangement is for compactness. It is driven from a shaft 131 which in 50 Fig. 4 is shown as having gear connection 132 with listing shaft 18.

Each unit comprises a reading-in commutator 133 and four reading-out commutators 134, the latter making one revolution for every card cycle 60 and the former a half revolution for each card cycle. Associated with each card column used for alphabetical recording is a pair of brushes 135X and 135R (Fig. 11) in cooperation with commutator 133. As the "X" position of the card is being analyzed brush 135X is in contact with segment 136X and as the "R" position of the card is being analyzed brush 135R is in contact with segment 136R. A perforation in either the "X" or "R" position will complete a circuit through 65 its associated segment and brush to energize either of a pair of magnets 137X or 137R accordingly as the perforation is in the X or R position. The armatures 138 of these magnets (see also Fig. 17a) are adapted to normally latch spring- 70 pressed brush structures 139"X" and 139"R" so

their brushes are in continual contact with the insulating portion of the commutator 134. Upon energization of magnet 137R, brush structure 139R will be permitted to shift into the plane of travel of conducting segment 140R. Similarly, energization of magnet 137X will shift brush 139X into the plane of segment 140X. As the frame 113 (Fig. 6) is rising to select the proper zone for alphabet printing, segments 140X and 140R will control circuits to energize magnet 120 at the proper time to advance either plunger 122 or 123. These circuits will be traced in detail in connection with the description of the circuit diagram.

Carried by the driving gear of each commutator is a cam member 141 which at the proper time in the cycle engages a pivoted lever 142 whose free end will thereupon engage and rock the brush structures to normal latching position.

It will be understood that brush structures 139X, 139R are tripped during the latter part of a card cycle, while the card is passing the upper analyzing brushes UB and that the circuits controlled by segments 140X, 140R are completed during the following cycle as the card is passing the lower brushes LB so that there is a concurrent 100 selection of a particular type in a zone and a selection of the zone itself.

Hammer locks

Means are provided to suppress the operation 105 of the printing hammers in the alphabet printing section of the machine during total printing operations when the alphabet type bars are not utilized to record totals. In Figs. 6 and 8 a pair of magnets 143 is provided which, upon energization, 110 is adapted to rotate a pivoted armature 144 to draw downwardly upon a link 145 which through bell crank and link connection 146 rocks a bail 147 in a counterclockwise direction as viewed in Fig. 6. Adjustably mounted on bail 147 are several 115 locking plates 148 which may be secured in either upper or lower position by suitable thumb screws 149. Upon rocking of bail 147 such plates 148 as have been set in lower position will descend with bail 147 to a position wherein their lower edges lie 120 in the path of the ends of hammers 105 thus preventing counterclockwise rotation of the hammers for printing action. It is obvious that by suitably selecting adjusting plates 148, the action of any or all of the three banks of alphabet type hammers may be suppressed under control of magnet 143.

In the numerical type bar banks of the machine individual hammer locks 150 (Figs. 5 and 8) are provided. These locks are suitably pivoted as 130 shown and when rocked to horizontal or locking position may be retained by plates 151 held in place by suitable thumb screws.

Zero pawl structure

135 In the numerical type bar (Fig. 5) section of the machine, the usual zero pawls 152 are provided to control positioning of the type bars in zero printing position under control of a significant figure in higher denominational order bars. 140

Similar pawls 152a are provided for the same purpose which are adapted to be controlled by the alphabet type bars 86a (Figs. 6, 8 and 9). These pawls are divided into three banks, each of which is carried by a lever 153 pivoted at 154. With 145 lever 153 in the position shown, its bank of zero pawls is moved sufficiently to be out of cooperation with type bar 86a while when lever 153 is rocked in a counterclockwise direction pawls 152a cooperate with the bars to control zero printing 150

in the well known manner. Levers 153 are locked in position by engagement of a bar 155 with either of notches 156. To shift the levers, bar 155 is retracted and the bar again advanced after a setting of the levers 153 has been made. While a bank of pawls 152a has been shown as being controlled by a single lever 153 it is obvious that the pawls may be carried by individual levers to permit moving one or more into or out of action 10 separately.

Dial switches

Several gang switches of the dial type are used in the machine to effect the control of a plurality of circuit connections concurrently by positioning a single knob or handle. One of such switches is illustrated in Fig. 22 and there is one of this type associated with each of the six accumulating counters 12. Fig. 23 shows the various operating conditions for which the setting 15 of the switch will control its associated counter. A cylindrical member 157 has groups of contacts 158 and 159 on its inner surface, each contact being provided with a binding post by which it may be wired to one of the machine circuits. 20 The group of contacts 158, located in pairs of two circumferential rows are the total selecting contacts. The several pairs may be bridged, one at a time, by a pair of connected, spring biased contacts 160 carried by a member 161 fast to a sleeve 25 162 freely supported on central rod 163. At its outer end this sleeve carries a knurled knob 164 by which it may be turned to selectively bridge any pair of the contacts 158. An indicator 165 30 is fixed to the knob 164 which may cooperate with suitable marks or legends as shown in Fig. 23 to show which pair of contacts is bridged.

The group of contacts 159 is arranged in three circumferential rows and the contacts are bridged in pairs by pairs of electrically connected spring biased contacts 166. Three pairs of contacts 40 coact with the lower and middle rows of the group and one pair coacts with the middle and upper rows of the group. The spring biased contacts 166 are carried by a member 167 fast to control rod 163 which carries at its outer end a knurled knob 168 by which it may be turned and an indicator 169 45 for indicating its position. It will be obvious then that by turning the knob 168 to different positions, different combinations of pairs of the contacts 159 will be bridged.

The circuit connections controlled by knob 168 and contacts 166 have been fully traced and explained in the patent to Daly and Page, No. 1,896,540 and will not be repeated here. The 55 switches are shown diagrammatically on the circuit diagram and their functions will be explained in connection with the diagram.

Several other dial switches are provided of similar construction which control certain alphabetical printing circuits and motor circuits. These have also been shown diagrammatically and will be explained in connection with the wiring diagram.

General features of circuit diagram

65 It may be explained that in tabulating machines of this type, it is common to utilize cam contact devices for controlling certain circuit operations. For clarity in the circuit diagram all cam contact devices which are operated in unison 70 and are mounted on common shafts are given similar reference numerals. For instance, there is a group of contacts marked P1, P2, P3, etc. mounted on one shaft and which function during totaling and resetting and another group 75 marked L1, L2, L3, etc. on another shaft func-

tion during listing. All cam contacts are insulated from each other and from the shaft upon which they are mounted. In placing these cams on the diagram they have been located without regard to their mounting upon common shafts in 80 order to obviate the complications of the circuit connections. Similarly for clarity in the diagram, it is necessary to place certain relay contacts at points remote from their controlling coils. In this case the contacts are labelled with the 85 reference character of their controlling coil with a lower case letter appended thereto, and the controlling coil has been shown in dotted outline adjacent to its related contact points.

Miscellaneous contacts

90

Several contact devices are provided whose functions will appear in the explanation of the wiring diagram. In Figs. 14 and 24 an arm 170 secured to rock shaft 87 is adapted to permit opening of a pair of contacts 171 immediately upon rocking the shaft to raise the type bar frame 95 94. Shaft 107b (Fig. 14) carries a commutator device 172 having brushes 173 cooperating therewith whose function is to open the circuits to the 100 printing magnets during listing operations to thereby prevent zero printing under control of the record card.

In Figs. 3 and 4 a pair of brush and commutator devices 174 is driven from counter shaft 26 105 by gearing 175. The commutators 174 are alike in structure and are set 180 degrees apart for alternate cooperation with their respective brushes. These commutators serve to control the entry of data into the inverter counters so that 110 entries may be made into a counter every second cycle and readings may be taken therefrom in the intermediate cycles.

Motor circuits

115

The tabulating motor TM is of the three speed type having speeds generally designated as low, intermediate and high and automatic shifting of the machine speed may be effected under control of the switch controlled circuits about to be 120 described. In general these speed-changing conditions are occasioned in accordance with the following accumulating and printing conditions.

First: When the machine is set for alphabetical listing it will operate at its slowest speed. 125 It will be understood however that during total and resetting operations, the machine is driven by reset motor RM whose speed is constant under all conditions and whose operation is independent of the tabulating motor.

Second: When the machine is set for numerical listing it will operate at its intermediate speed.

Third: When the machine is set for numerical indicating or listing from the first card only of 135 each group and accumulating only, from the balance of the cards, the machine will perform the first card listing operation at its intermediate speed and the following accumulating operations at high speed.

Fourth: When the first card indication is to be alphabetical and accumulating only is to take place for the remaining cards of a group, such first card indicating will occur at slow speed and the accumulating will take place at high speed.

Fifth: Where alphabetical indicating is to take place for the first card and numerical listing for the remaining cards such indicating will be at slow speed and the following numerical listing will be at intermediate speed.

140

145

150

- The various circuit conditions necessary to effect the several speed changes will now be traced in connection with the circuit diagram (Fig. 25). It will be assumed that the usual reset cycle which will later be traced in detail has been completed, permitting closure of the motor control relay points 180a so that upon depression of start key ST the following circuit will be established. From side of line 181 through reset interlock relay points 182a, clutch magnet contacts 183 card feed clutch magnet 184, clutch relay 185, start key ST, motor control relay points 180a, (now closed) stop control relay points 186a, contact P1 to other side of line 187.
- 10 Energization of magnet 184 will cause opening of contacts 183 so that current will now flow through tabulating interlock relay 188 and also motor relay 189. Points 188a of relay 188 are located in the reset circuit to prevent energization thereof while the feed clutch circuit remains completed.
- 15 Energization of relay 189 will close its points 189a in the motor circuit which will then be completed from line 181, points 189a, motor TM, start relay 190, contact P1 to line 187. Relay 190 will close its points 190a to permit starting the motor under low speed characteristics regardless of the set-up of the speed controlling switches when the motor is put into operation. The relay 30 190 is adjusted so that its contacts close on the heavy starting current but open as soon as the motor attains normal speed thus providing for high starting torque under all conditions.

- As cards proceed to feed through the machine 35 the upper card lever relay circuit is completed from line 181, wire 192, upper card lever relays UCL1, UCL2, UCL3, card lever UCL to line 187. Similarly, upon closure of the lower card lever contacts LCL the circuit is completed from line 40 181, wire 192 relays LCL1 and LCL2, wire 193, contacts LCL contact P1 to line 187. Closure of points UCL2 short circuits the start key contacts ST in the usual manner to maintain the feed clutch circuit in operation until the cards are 45 exhausted from the supply hopper.

- During numerical or alphabetical listing, contact LC2, closed whenever the listing cam is in motion, will shunt out resistance 194 to effect operation of motor TM at its intermediate speed 50 by causing current to flow from the winding 191, contact LC2, resistance 195 to line 187.

- Toward the end of the first cycle of the list shaft, closure of contacts L23 will complete a circuit from line 181, wire 192, relay 196, contacts 55 L23, wire 248, card lever contact UCL to line 187. A stick circuit through points 196a will hold this circuit from relay 196, points 196a, wire 197, points 198a of the group indicating relay 198, contact P7 and back to line 187 through wire 60 193 and contacts LCL and P1. This circuit continues until a total and reset cycle is effected wherein opening of contacts P1 interrupts it. When the type bars are in their restored position contacts 171 (Fig. 24) are closed and a circuit 65 may be completed as follows: from line 181 wire 192 relay coils 199, 200, 401, contact 171, points 196a (now closed) and thence to line 187 through remainder of stick circuit traced above. Coil 401 closes its points 401a to create a holding circuit for coils 199 and 200 which circuit will also be held until P1 breaks during a reset cycle.

- This initial energization of coil 200 influences the type of operation of the motor TM and coil 199 controls the stopping conditions. With dial 75 switch 201 set for alphabetical listing its contact

points in position A will be bridged and the motor winding circuit will be shunted around both resistances 194 and 195 for low speed characteristics. This circuit is from winding 191 through contacts LC2 (which close under all listing conditions) wire 202, bridged points of switch 201 in "A" position and thence to line 187. With dial switch set for numerical listing neither of the contact points of the dial switch 201 are bridged and only resistance 194 will be short-circuited, the circuit being from winding 191 through contacts LC2, resistance 195 to line 187. The motor TM will accordingly operate at its intermediate speed.

With the machine set for numerical indicating and tabulating, the normal first listing cycle will close contacts LC2 and the group indication will occur at intermediate speed. During the following tabulating cycles, contact LC2 remains open and both resistances 194 and 195 will be included in the winding circuit for high speed operation.

With the machine set for alphabetical indicating and tabulating the contacts in the B position of dial switch 201 will be bridged so that on the 10 listing stroke with LC2 and 200A closed resistances 194 and 195 are shunted for slow speed operation. Following the indicating cycle contacts LC2 open in the usual manner and contacts 200a open under control of the group indicating 100 circuits, in a manner to be explained, so that the subsequent tabulating operations proceed at high speed.

With the machine set for alphabetical indicating and numerical listing, the same conditions 110 prevail on the first printing cycle, but since the type bars are permitted to rise during each subsequent cycle contact LC2 will close to effect operation at the intermediate speed, points 200a again opening after the first cycle.

The usual cam contact L1 is provided, which is wired in parallel with the clutch circuit breaking contacts and whose function is to time the actual interruption of the circuit so as to obtain the proper coasting conditions for bringing the parts 120 to rest in home position. Opening of contacts L1 will provide the proper break when the machine is operating at high speed. For intermediate and low speed operation a second contact L2 is provided which is adapted to maintain the circuit for 125 a longer period since with the parts moving at a slower speed a lesser coasting time is required.

Inclusion of contact L2 in the circuit is controlled by dial switch 203 which may be operated in common with switch 201, so that during numerical listing, contact points in position C are bridged while when alphabetically listing the points in position D are bridged. Included in the circuit through the D position of switch 203 are the points 199a of relay coil 199 which as will 135 hereinafter be explained are opened by the group indicating circuits after the first printing operation for each group of cards.

Stop key circuit

Depression of stop key S will energize stop control relay 186 through a wire 204 from line 181 contacts L18, L19, contact S contact P1 to line 187. Inclusion of contacts L18, L19 in this circuit prevents completion of the circuit except at a 145 predetermined point in the cycle of the machine. Energization of coil 186 opens its points 186a to interrupt the feed clutch circuit and closes its points 186b to effect a stick circuit through coil 186 and contact L18 which will hold until contact 150

L18 breaks. The machine will thereupon stop under control of contacts L1 and L2.

Reset circuit

5 A reset cycle of the machine may be initiated by depression of reset key R which will establish the following circuit: from line 181 contact R, reset interlock coil 182 contact P3, relay points 188a which are closed only if the feed clutch is 10 deenergized, coil 205, reset clutch magnet 48, wire 206 contact L5 to line 187. Energization of clutch magnet 48 will close its associated contacts 209 completing the circuit from line 181, contacts 209, parallel coils 143, 207 and 208, wire 206, contacts L5 to line 187. Coil 207 closes its points 207a completing the reset motor circuit from line 181 motor RM, points 207a wire 206 to line 187 as before.

20 With the reset motor running, the total shaft revolves carrying with it the P cams, of which cam contact P4 closes to hold the circuit through coils 143, 207, and 208 until the end of the reset cycle when it will open to stop motor RM.

25 This reset operation may also be automatically initiated upon stopping of the machine if auto reset switch 210 is closed. In such event, closure of contact L4 at the end of the last tabulating or listing cycle will short-circuit reset key R and effect a set-up of the reset motor circuit in the same manner as traced above.

30 If auto start switch 211 is closed and the presence of a card at the lower brushes causes closure of contact LCL2, closure of cam contact P2, at the end of the reset cycle will automatically restart the machine by shunting clutch relay contacts 185a thus setting up the feed clutch circuit traced above, provided reset interlock relay contacts 182a, 182b have resumed the position shown on the diagram due to interruption of the reset circuit. The reset clutch circuit is interrupted by the opening of contacts P3 near the end of the reset cycle which of course deenergizes the interlock relay 182. If, however, the machine is operating under automatic controlling conditions 45 and major total taking operations are being performed reset magnet control contacts 212a will be closed during the first reset cycle at the time P3 opens thus preventing the interruption of the reset clutch circuit. A second reset cycle will then ensue during which contacts 212a open to permit control by P3 in the usual manner.

Automatic control circuits

50 The major and minor automatic control system used in the present machine will be briefly described to bring out certain selective features. In Fig. 25a upper analyzing brushes UB coact with a common bar which is connected to main line 181 through cam contact L8. The lower analyzing brushes LB coact with a common bar which has electrical connection 213 with one brush of the usual impulse distributor T1. The energizing circuit for these brushes extends through T1, wires 214, 193, contacts LCL and P1 to line 187. The common bar of the lower brushes will thus be energized for each index point position of the record cards provided the tabulating motor and card feed clutch are operating and cards are 55 passing the lower brushes to close contacts LCL. The record cards bearing numeral designating perforations pass successively between upper brushes UB and their common bar.

60 The automatic control magnets 73 (Fig. 25a) are provided with the usual spark preventing con-

65 tacts in series therewith and each magnet is connected by suitable plug wires in series between any upper and lower analyzing brush in the well known manner to effect automatic control from any card column. The automatic control contacts 72 of which one is associated with each control magnet, are arranged to close individually when the corresponding control magnet is energized and all of them open simultaneously towards the end of each tabulating or listing cycle. When the control perforations on successive cards under the upper and lower analyzing brushes agree all control contacts 72 which are properly 70 plugged close at some time during the cycle, while, when the control perforations fail to agree, one or more of these contacts fails to close.

75 The automatic control contacts 72 are all connected in series and a socket 215 is provided between each pair of them so that any number may be utilized and the control split into major and minor sections at any point. Cam control contacts L7 govern the operation of the machine under major control and cam control contacts L6 govern under minor control. Both of these contacts are normally closed but open for an instant 80 towards the end of each tabulating or listing cycle. If the perforations in both cards have agreed the minor control circuit will be sustained through the following circuit from line 181, wire 216, contacts 217a of minor relay 217, (closed during the 85 previous reset cycle), coils 218, 219, contacts 72, plug connection 220, upper card lever relay contacts UCL1 wire 221 to line 187. A similar circuit extends from wire 216 through contacts 222a of major relay 222 (closed at this time) plug connection 223 major control contacts 72 plug connection 220 back to line 187 as before. In this manner upon opening of contacts L6 and L7, minor relay 217 and major relay 222 are kept 90 energized through contacts 72 since at the time L6 and L7 open the card lever relays UCL1 and UCL3 are also open. During the remaining portion of each card cycle the circuits through relays 217, 222 extend through the relay points LCL1, UCL3, and cam contacts L6 and L7.

95 A disagreement in the minor control field evidenced by failure of a contact 72 to close will cause deenergization of coil 217 and the consequent opening of its points 217a and closure of its points 217b. It is to be observed that the minor 100 control circuit extends through the major contacts 72 also, so that failure of a contact 72 in the major section of the control contacts will also cause failure of the minor control circuit.

105 Failure of the major control circuit will in addition cause deenergization of its control relay 222 and the consequent opening of its points 222a and closure of its points 222b. In either event, a circuit is completed from line 181, wire 216, contacts 217b or 222b to motor control relay 180, 110 reset magnet control relay 212 and wire 221 to line 187. Energization of coil 180 opens its points 180a (Fig. 25) to interrupt the tabulating motor circuit and the machine will either stop or enter upon an automatic total printing and reset cycle 115 during which totals are printed and counters reset in accordance with the setting of selective switches to be later described.

120 Assuming the break in the control circuit to have been in the minor section, minor relay 217 115 will have been deenergized together with coils 218 and 219 permitting the opening of their related points 218a and 219a. Near the end of the ensuing reset cycle closure of cam contact P6 will reestablish the minor control circuit energizing 125

coils 217, 218, 219 and if the machine is set for automatic restarting, card feeding will resume.

Where the break occurs in the major control, two reset cycles will take place before card feeding again resumes. This is effected by maintenance of the circuit heretofore traced through coils 180 and 212 for two successive cycles. Coil 212 holds its points 212a (Fig. 25) closed to short-circuit contact P3 as already explained so that a second reset cycle follows the first. During the first cycle minor relay 217 is set up upon closure of contacts P6. During the second reset cycle cam contact P5 which closes and opens again in advance of the closure of P6 may now complete the major set up circuit from line 181, wire 216, minor relay points 217a (now closed), cam contacts P5, major relay 222, contact L7, to line 187.

As is customary in machines of this type the automatic control circuits may be incapacitated by closing switches 224 in which case relays 217 and 222 will remain constantly energized.

Group indicating circuits

The usual group indicating feature in tabulating machines contemplates the entry of certain data from a single card of a group into an accumulator or listing bank and the suppression of further entries from the same data field into that particular accumulator or listing bank. In Fig. 25 the group indicating control relay 198 has its points positioned as shown after each reset cycle, so that the following circuit may be traced: from line 187 contacts P1 and LCL, wire 193, contacts P7 and 198a, wire 225 which feeds current to the alphabet zone selecting read-out devices through a dial switch 226 (Fig. 25a) and to the printer magnets 99 and 99a through dial switches 227 (Fig. 25b) whose operation will later be explained. If switch 228 is set as shown in Fig. 25, current will also branch from line 225 through switch 228, cam contacts L11, multi-contact relay magnet 230, wire 192 to line 181. Energization of magnet 230 will cause closure of its contacts 230a to connect list magnets 99a of one bank of alphabetical type bars to line 181 through wire 231.

Toward the end of the first tabulating or indicating cycle as it is called, cam contacts L9 close momentarily to set up a circuit from line 181, wire 192, coils 232 and 198, cam contact L9, wire 193 to line 187. Coil 198 will thereupon close its points 198b to establish a holding circuit through cam contact P7 and open its points 198a to interrupt the current to wire 225 and the devices supplied thereby. This holding circuit will remain energized until the following reset cycle when it is broken by the opening of contacts P1 and P7.

Adding and numerical listing circuits

The machine is provided with six accumulating counters of which four are designated diagrammatically in the circuit diagram (Fig. 25b) as CTR#1, CTR#2, CTR#3 and CTR#4, while two additional counters CTR#5 and CTR#6 are indicated. Each counter magnet 35 is connected to an individual socket 233 through which it may be plugged to any desired lower analyzing brush or other entry device. The lower analyzing brushes as previously explained receive an energizing impulse whenever they encounter perforations in the record cards and thus supply timed impulses to the counter magnets to effect entry of the data represented by the perforations. The circuits enter from brushes LB

through suitable plug wires to sockets 233, magnets 35, series contacts 234, wires 235, to line 181. Contacts 234 are the usual series contacts which open as soon as the magnet 35 is energized to prevent sparking at the analyzing brushes. Associated therewith are also the usual listing contacts 236 which close as soon as the counter magnet is energized and close the circuit to the associated printing magnet 99 for listing purposes.

The listing contacts of CTR#3, CTR#4, CTR#5 and CTR#6 are directly connected to the printer magnets 99 of the corresponding numerical printing banks. They are also provided with sockets 237 through which connection may also be made to the printer magnets in other banks for duplicate listing.

The listing circuits are controlled by dial switches 227 of which there is one for each counter. The switches are settable for four conditions, namely; adding, listing, indicating and subtracting. When set in "List" position, printing of the added items will be an accompaniment to such accumulating and upon closure of a listing contact 236 current will flow from line 181, wire 235, contact 236 magnet 99 common wire 238 to dial switch 227 which if it is set as the one shown adjacent to CTR#1 will complete the circuit to wire 239 through fixed dial connection 240 and thence to line 187.

With dial switch 227 set as "Add" position as shown adjacent to CTR#3, the listing circuit will not be completed through connection 240 and consequently the items entered in the associated counter will be added without accompanying listing.

With the switch 227 set at "Indicate" wire 238 will be connected to wire 225 through fixed dial connection 241 as indicated opposite CTR#2. Since, as has been pointed out in connection with the group indicating control circuit, wire 225 receives current only during the first card cycle of each group, it follows that the listing circuits through dials set at "Indicate" will print only the item entered as the first item of each group and the circuit connection for the following cards of the same group will be incomplete.

With the dial switch 227 set at "Subtract" the same conditions prevail as when adding, that is, the listing circuits remain broken so that an entry in the counter is not accompanied by printing. The position of the movable contacts of the dial switch for this position are shown adjacent to CTR#4.

Alphabetical listing circuits

CTR#1 and CTR#2 are shown diagrammatically in Fig. 25b as being associated with two of the three alphabetical listing banks and have their list contacts 236 terminating in plug connections 242 which when it is desired to list the items entered in such counters upon these alphabetical listing banks will be plug connected to sockets 243 which are wired to the alphabetical printing magnets 99a. Each of these two listing banks has a three-position dial switch 244 associated therewith which when set at "Numerical" will complete the listing circuit upon closure of list contact 236, from wire 235, contact 236, socket 242, plug connection to socket 243, list magnet 99a, connection of switch 244 to wire 245, cam contacts L20 or L21, wires 238a through switches 227 as before, completing the circuit in accordance with the setting of the latter dials. Contacts L20 and L21 open after the "One" in-

dex point position of the card has been sensed to prevent energization of magnets 99a at zero thus permitting zero printing to be effected under mechanical control of higher denominational order type bars.

For alphabetical listing independent of adding, switches 244 are set at "List" and the lower brush sockets are directly plug connected to sockets 243 of the magnets 99a for columns to be controlled. The listing circuits will then follow from impulse distributor T1 (Fig. 25) wire 213, lower brush common, brush LB, plug connection to socket 243, magnet 99a common wire to switch 244, contact connection to wire 246, cam 15 contact L22 to line 181.

With dials 244 positioned at "Indicate" these circuits will go through group indicating relay points 232a instead of wires 246 and since, as above explained, coil 232 is energized after the 20 first card cycle, these circuits will be incomplete for succeeding cards due to the opening of points 232a.

The zone selecting circuits are shown in Fig. 25a. Plug connection is made from upper brush 25 sockets to sockets 247 in the columns corresponding to those in which connections have been made to sockets 243 from the lower brushes. If the column analyzed by brushes UB contains no "X" or "R" perforation there will be no zone set-up. If an "X" hole is present a circuit follows from line 187, contact UCL (Fig. 25) wire 248, contact L24 which closes at the "X" point in the cycle, wire 249 to commutator 133; thence through brush 135X to magnet 137X, plug socket 35 247, plug connection to brush UB, contact L8 to line 181. Had the perforation occurred in the R position a similar circuit would have been completed through contact L25 closing at "R" time and thence through brush 135R to magnet 137R.

This, as has already been pointed out, shifts the read-out brushes 139X, 139R to select the proper printing zone during the following card cycle. The zone selecting circuits may be traced from line 181, wire 250, magnets 120 common brush and ring of commutator 134 to either the X or R brush 139X, 139R (if either has been shifted to cooperate with its commutator segment) wires 251, 252 to cam contacts L26, L28 50 wire 253 to dial switch 226. With switch 226 set at "List" the circuit will continue through wires 254, 193 to contacts LCL and P1 to line 187. If switch 226 is set at "Indicate" the circuit continues through wire 225, contacts 198a, P7, LCL, P1, to line 187. Since contacts 198a 55 open after the first card cycle as explained, the zone selecting circuits will also be ineffective in the same columns in which listing is suppressed.

Total printing circuits

60 The total printing circuits include printing magnets 99 and 99a and read-out commutators 40, 41 and associated emitters 49. Gang contacts 64 are closed in a manner to be explained in those banks from which totals are to be printed. It has already been pointed out that emitter brushes 51 revolve during the total and reset cycle and emit a series of impulses through segments 50 to wires 255 in succession as the corresponding type elements pass through printing position. Brushes 39 have previously been positioned by the entering devices and will occupy differential positions in accordance with the value entered thereon. Assume a brush 39 to be set at 7 in CTR#4 (Fig. 25b), then, as the brush 75 51 traverses its commutator a circuit will be

completed at the "7" point in the cycle as follows: From line 181, master relay points 205a (Fig. 25a) (closed only when the total and reset clutch circuit is completed) wire 256, wire 257, brush 51, "7" segment 50, "7" wire 255, brush 39 to the common strip 41 of the column containing the "7", closed contact 64, magnet 99, wire 238, wire 240 of switch 227, wire 258, commutator 259, contact P9 to line 187. Commutator 259 is on the listing cam shaft 107b and is adapted to close the circuits when the listing cam is idle.

Counter reset selection

Following the total printing operation, the counter from which printing has taken place may be reset in the usual manner by energization of its zero button magnet which couples the counter to the reset shaft. The selective operation of contacts 64 and zero button magnets 58 is controlled by dial switches 260 (Fig. 25a) of which there is one for each counter. In addition to an "Off" position the switch may be set to cause its coupler to total print without resetting, total print and reset, and major total print and reset.

The operation of the selecting dial switches 260 may best be understood from the circuit diagram (Fig. 25a). Each switch includes a pair of diametrically opposed sliders 275 which may be rotated to the several selecting positions on the switch. With the switch 260 in major total and reset position, the zero button magnet 58 associated with the particular counter bank corresponding to the switch is connected to main line 181 through the relay points 208a whose controlling coils 208, it will be recalled, are in the resetting circuit. For the purpose of explanation, dial switch 260 indicated as #4 is shown in the major total and reset position, switch #3 in the 115 total and reset position, switch #2 in the total only position, and switches 1, 5 and 6 in their off position. It will be understood, of course, that this particular set-up would, in all probability, never be encountered in practice and it has been assumed merely to explain the operation of the 120 dial switches. Their purpose is to provide for closing all circuits which must be closed to perform the selected operation and to open all circuits which could by any possibility interfere 125 with the selected operation. With the switch 260 in position as at #4, the associated counter is selected to print totals and reset only on a change in group data in the major control section. It will print and clear, of course, during the second 130 reset cycle when the zero button control magnet 218 is energized as previously explained, to close its points 218a.

During the total printing cycle of the machine the following circuit may then be traced: from line 181, through closed relay points 208a, #4 zero button magnet 58, switch contact slider 275, to wire 276, relay points 218a, wire 277, to line 187. The energization of the zero button magnet 58, 135 it will be recalled, clutches the counter elements 140 to the reset shaft for restoration of the former to zero position.

A second circuit may also be completed from line 181, through relay points 205a whose controlling coil is energized during the initiation of 145 a total print cycle, a wire 278, through dial switch 279 in a manner to be explained, magnet 68, to the second slider 275 of the #4 dial switch 260, wire 280, relay points 219a (which operate together with points 218a) wire 277, to line 187. 150

Energization of magnet 68 will cause closure of its associated contacts 64 disposed in the total printing circuits of the corresponding counter #4 to permit the completion of the total printing circuits 5 as already traced in detail.

The total selecting switch 260 in total and reset position, as indicated by #3 switch, connects its zero button magnet 58 through the switch to a wire 281 connected directly to wire 277 and line 187 whereupon closure of the relay points 208a in any reset cycle will cause the counter to print totals and clear. Such counter would, of course, print and clear on a change in the minor section of group control, if the machine were under major 15 and minor control and also on a group change with the machine under straight automatic control.

With the switch 260 in total only position, as indicated at #2, the zero button magnet circuit 20 is open entirely and there can therefore be no resetting of the #2 counter. The circuit through magnet 68, may, however, be completed to wire 281 and thence to line 187 to effect closure of the total printing circuits. Thus in any total without 25 reset cycle the counter prints its total and retains its set-up. This permits the printing of so-called progressive totals at any time.

With the dial switch in off position as at #1, neither of the circuits through the magnets 58 30 and 68 can be completed.

Class selection

It is often desirable to represent items of different classes in the same columns of the controlling records but to enter the items of the different classes into different accumulators. Debit and credit items are often handled in this way either for entry into the different accumulators for separate addition of the classes or in subtraction for selecting the different balance accumulators in which true numbers of complements are to be entered. The cards containing items of one class are identified by a perforation in a selected column. This perforation is located 45 on the trailing portion of the card in the "X" position which reaches the analyzing brushes after they have completely sensed all item entry 50 controlling positions. This perforation in the "X" position is omitted on cards bearing items of the other class. A class selecting relay 282, shown at the bottom of Fig. 25, has one terminal connected directly to line 187 through a wire 283 and its other terminal connected through cam contact L13 to a plug socket 284. The socket 284 may 55 be plugged to the upper analyzing brush socket whose brush cooperates with the card column in which the "X" designation perforation occurs. The cam contact L13 closes after the brushes leave the last item perforation position and remain closed until they encounter the "X" position. 60 Any card bearing a perforation in the "X" position closes the circuit of the relay 282 while any card not bearing such a perforation does not. The relay when energized closes its points 282a 65 completing the circuit from line 181, cam contacts L12 which are closed at this time, relay points 282a, relay 282, a relay 285, wire 283, to line 187, thus forming a stick circuit for the relay.

Cam contact L12 is timed to hold this circuit 70 until after the analysis of the last item perforation position of the card by the lower brushes during the next succeeding cycle of the machine when, incidentally, the items from the card are being entered into the accumulating or indicating devices. A multi-contact relay 286 is in parallel

with relay 282 and is energized and deenergized with it under control of a cam contact L14 which is adapted to close shortly after the sensing of the "X" position and to remain closed until after the item entering period of the succeeding cycle. The relay 286 controls contacts 286a (Fig. 25a) of which the middle one of each group is connected to a socket 287. The upper one of each group is connected to a socket 288 and the lower one of each group is connected to a socket 289. The middle contacts of all groups 286a are shiftable by the relay 286, when energized, from their normal position in engagement with the lower contacts of the group into engagement with the upper contacts of the group. Then, if sockets 287 are plugged to the lower analyzing brushes or other entry controlling devices and sockets 289 are plugged to the counter magnet sockets 233 of one accumulator bank while sockets 288 are plugged to the counter magnet socket 233 of another accumulator bank, it is obvious that one bank will receive items from cards punched in the "X" position and the other bank will receive items from cards not so punched.

Unused columns

Relay coil 285 in series with class selection relay 282 is adapted to control a plurality of contacts 285a (Fig. 25a) in the same manner as relay 286 controls contacts 286a. The middle contacts of each 285a group is directly connected by a wire 290 to a brush of impulse distributor T1.

These contacts have utility in the accumulating of debit and credit balances by rendering unnecessary considerable plugging connections heretofore required; for instance, in accumulating debit and credit balances, a single accumulator is devoted to the accumulation of true credit items and the complements of debit items while another accumulator will receive true debit items and complements of credit items. Where the capacity of a counter is, let us say, of nine denominational orders and the items are being derived from a card field of say four places, it has heretofore been necessary when converting a true number into its complement to add sufficient nines to the left of the number to accommodate the capacity of the counter into which it is to be entered; for instance, in converting the number 8721 into its complement 999991279 that nine places are now present. This means that any mechanism for translating or inverting the true number 8721 into its nine place complement requires sufficient capacity to handle the latter number. This has formerly been done by providing a nine order translating mechanism. With the present arrangement, however, the capacity of the translating mechanism may be reduced to the size of the field of the record card from which the translating devices are being controlled. The extra nines necessary to fill out the complement are derived from the impulse distributor T1 which as the distributor rotates during entering cycles will emit an impulse at nine (to wire 290 and through contacts 285a and through either sockets 291 or 292, to the columns of the balance counter which are to receive the complements). In the example noted, five such sets of contacts 285a would be plugged to the proper columns of the pair of balance accumulators.

Subtracting

The manner of subtracting will now be briefly explained. It is performed by throwing each item into one balance accumulator in true value and

into another balance accumulator in its true complementary value. The true values of the debit items go into one balance accumulator and the true values of the credit values go into the other.

5 At the end of a subtracting run, if the balance represents a debit, it will appear in its true value on the one accumulator and in its complementary value on the other. The balance must be printed from one accumulator only, of course, and the 10 one it is to be taken from depends on whether it represents a debit or a credit balance. At the end of each subtracting run, one of the accumulator wheels to the left of each bank is felt out for the nine position as the presence of a nine indicates a complement. The feeling mechanism 15 when it encounters a nine, then automatically selects the other accumulator to print the balance.

The complements of the items are obtained 20 through so-called inverting counters whose mechanism has heretofore been explained. The two separate sets of inverting counters 13 shown in Fig. 1 are used as means for alternately storing and inverting readings of numbers read from 25 punched cards passing through the tabulator. While one inverter counter is receiving the results of reading a card under the upper brushes, the complement of the number standing on the other previously operated inverter counter is being 30 transferred to the debit or credit balance counter. The inverter counter from which the complement is being transferred is reset simultaneously with the transferal, thus conditioning it for the reception of a number on the next card cycle.

35 A complement may be read from one or the other of the inverter counters during each card cycle. The devices for selecting which balance counter is to receive the complement and which balance counter the true number are controlled 40 by a special hole in a debit card. This hole may be the same perforation which actuates the class selection relays 282 and 286.

The inverter entering circuits are shown in Fig. 25a. As the record cards pass the upper brushes 45 UB a circuit may be completed from line 181, contact L8, perforations in the record card, brush UB and a suitable plug connection to sockets 293 which are connected to the entering magnets 35 of the inverting counters. The circuit 50 continues through the usual circuit breaking contacts 234, commutator 294, wire 295, to an impulse distributor T2, and thence through wire 243 and upper card lever contact UCL, to line 187. A pair of commutators 294 are provided 55 which cooperate to alternately connect the two inverting counters to the distributor T2 so that entries are made into these inverting counters in alternate cycles. The read-out devices of the two inverting counters are shown diagrammatically in Fig. 25a directly above emitter 296 and have their common conducting segment 41 connected to commutator devices 297 which function to alternately connect the read-out devices to the center blades of a plurality of contacts 60 298a. The contacts 298a are controlled by a relay 298 which in Fig. 25 is shown wired in parallel with class selection relay 286 which, as has been explained, is energized under control of a special perforation in the record card.

65 70 The lower blades of contacts 298a are connected to plug sockets 299 and the upper blades are connected to plug sockets 300. A plurality of contacts 298b are also provided whose lower contacts are connected to sockets 300 and whose upper contacts are connected to sockets 299.

The middle blades of contacts 298b extend to sockets 301 which may be suitably connected to the plug sockets of the lower brushes LB.

The present machine is arranged so that debit and credit balances may be accumulated on 80

counters #3 and #4 or on counters #5 and #6. The manner in which these balances are accumulated in counters #3 and #4 will now be briefly explained. Assuming that it is desired to accumulate credit balances on 85

counter #3 and debit balances on counter #4, the plug sockets 233 connected to the accumulating magnets of counter #3 will then be connected to plug sockets 300 and the plug sockets 233 of counter #4 will be connected to sockets 90

299. As a record card is passing the upper brushes UB, circuits will be completed through the entering magnets 35 of one of the inverting counters to enter the value contained on the record card into the inverting counter. Assuming 95

the item entered to be a credit amount, during the next succeeding cycle as the record card is passing the lower brushes, circuits will be completed from wire 214 to the brush of emitter 296 and thence to the read-out device of the invert- 100

ing counter which received an entry in the previous cycle. The circuits then extend through a commutator 297, middle and lower blades of contacts 298a, sockets 299 and plug connections to counter #4. 105

Impulse emitter 296 is adapted to emit im- 110 pulses to the read-out devices of the inverting counters in accordance with the complementary values of the entries; thus, where an "8" is en- tered in an order of the counter, impulse emit- 115

ter 296 will complete a circuit in that position at the "1" time thus causing a circuit to be completed at the "1" time in the cycle to enter a "1" into the proper counter. The wiring is so 120 arranged that in the units order of each counter the impulses emitted are the tens complements of the entries and in other orders the numbers are complemented to nine. As the complement of this credit item is being entered into the debit balance counter #4 the true value of the num- 125

ber is entered into counter #3 directly from the lower brushes to plug sockets 301, middle and lower blades of contacts 298b, plug sockets 300 to counter #3. Thus, after a card bearing a 130 credit entry has completely passed the upper and lower brushes, the credit entry will have been transferred to counter #3 in its true value and into counter #4 in its complementary value.

Assuming the entry on the record card to be a debit item, the special "X" perforation will 135 then accompany the entry and as the card is passing the upper brushes entry will be made into one or the other of the inverting counters in the same manner as though the item were a credit item. At the same time the special per- 140

foration will cause energization of magnet 298 through the circuits already traced in detail. Magnet 298 will remain energized throughout the succeeding cycle and contacts 298a and 298b 145

will be shifted to close their upper contacts and open their lower contacts. This will reverse the entries into counters #3 and #4 so that the complementary values emitted from the read-out 150

devices of the inverting counters will extend through the middle and upper blades of contacts 298 to sockets 300 and thence to counter #3, thus entering the complement of the debit entry into such counter.

Also the direct reading from the lower brushes will extend through the middle and upper blades 150

of contacts 298b to sockets 299 and thence to counter #4 thus entering the true value of the debit item in such counter. The two inverting counters and their read-in and read-out controlling commutators 294 and 297 are arranged so that while one of the inverting counters is receiving entries, the other is being read out and vice versa. This arrangement is, of course, for convenience.

10 At the end of a run of cards, counter #3 will contain all the credit entries and the complements of the debit entry and counter #4 will contain all the debit entries and the complements of the credit entries and if the balance represents a credit, it will appear in its true value in counter #3. Conversely, if the balance represents a debit, it will appear in its true value in counter #4 and in its complementary value in counter #3.

15 The balance must be printed from one accumulator only, of course, and the one it is to be taken from depends upon whether it represents a debit or credit balance. At the end of each subtracting run, one of the accumulator commutator read-out elements is felt out for the nine position as the presence of a "9" indicates a complement. The feeling mechanism when it encounters a nine then automatically selects the other accumulator to print the balance. This

20 feeling mechanism is shown in Fig. 25b as comprising a special emitter segment 50a on each of the emitters 49 associated with counters #3 and #4. Brushes 51 are normally in engagement with these segments when at rest. Upon initiation of a total printing cycle of operations at the commencement of which relay point 205a close in the now familiar manner, a circuit will be completed through either counter #3 or #4, if such counter contains a complement.

25 Assuming the complement to be contained in counter #4, the circuit may be traced as follows: From line 181, Fig. 25a, relay points 205a, wire 256, wire 257 of counter #4, Fig. 25b, brush 51, segment 50a, segment 40 in the nine position of the highest order of counter #4, thence through brush 39 which will also be at nine, if the counter contains a complement, the conductor strip 41 and wire 305 which extends to the upper of two switches 279 in Fig. 25a. With switch 279 in "Bal." position as shown, the circuit will continue through switch slider 306 to magnets 68 associated with the #3 counter, and thence through the #3 switch 260 to right side of line 187, as explained heretofore. Magnet 68 when energized will, of course, select counter #3 for total printing. If the complement had been on counter #3, a similar circuit would have been completed from the common strip 41 of counter #3 to a wire 307, and thence through contact slider 308 of the upper switch 279 to and through magnet 68 of the #4 counter.

30 Switch 279 may be set in its alternate or total printing position as indicated by the lower switch 279. In such case the wires corresponding to 305 and 307 do not continue their circuits through switch 279 and the magnets 68 of the two associated counters are connected through wire 278 to the relay points 205a for total printing purposes in the normal manner.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims:

- What is claimed is,
1. In a cyclically operable record card controlled machine for tabulating data derived from groups of cards, an accumulating device, an alphabetic printing device and a numerical printing device, means for operating said devices separately, a 3-speed motor, a plurality of resistances for controlling the speed and torque characteristics of said motor, means for automatically cutting out one of said resistances during the first card cycle of a group, means governed by both of said printing devices for controlling the coaction of another of said resistances and said motor and selectively settable means for disabling said cutting-out means.
  2. A card-controlled printing tabulator for totaling data gathered from groups of cards, a 3-speed driving motor therefor, a plurality of resistances for controlling the speed of said motor, a plurality of different types of printing devices, means for selecting one of said printing devices for operation and means controlled by said selecting means for automatically cutting out one or more of said resistances, in accordance with the type of printing device selected for operation at the beginning of the first card cycle of a group and cutting in said resistance or resistances at the end of said first card cycle.
  3. In a cyclically operable record controlled machine for tabulating data derived from groups of records, a 3-speed motor, a pair of series connected resistances included in the field circuit of said motor, printing mechanism, means controlled thereby for cutting out one of said resistances, means for cutting out the other resistance during the first card cycle of a card group, and means for disabling said last named cut-out means.
  4. The invention set forth in the preceding claim in which a relay is provided and controlled in accordance with the starting current for said motor for cutting out both resistances.
  5. In a cyclically operable record controlled machine for tabulating data derived from groups of records, a 3-speed motor, means for conditioning said machine for alphabetic printing, numerical printing or accumulating operations, a pair of series connected resistances included in the field circuit of said motor, and means automatically operable in accordance with the type of operation to be performed for cutting out one of said resistances during numerical printing operations, and for cutting out both resistances during alphabetic printing operations.
